UNITED STATES PATENT OFFICE

167,485

EXHAUST EXTENSION FOR AUTOMOBILES

William B. Sandler, Newton, Mass.

Application December 15, 1951, Serial No. 17,750

Term of patent 14 years

(Cl. D14—6)

To all whom it may concern:

Be it known that I, William B. Sandler, a citizen of the United States of America, residing at Newton, Commonwealth of Massachusetts, have invented a new, original, and ornamental Design for an Exhaust Extension for Automobiles, of which the following is a specification, reference being had to the accompanying drawing, forming a part thereof, in which:

Figure 1 is a side elevation of an exhaust extension for automobiles, showing my new design.

Figure 2 is a top view of the same.

Figure 3 is a front view of the same, and,

Figure 4 is a rear view of the same.

The underneath surface of my design for exhaust extension for automobiles follows the same contour as in the views shown.

I claim:

The ornamental design for an exhaust extension for automobiles, as shown and described.

WILLIAM B. SANDLER.
